DRAFTING TABLE

Alfred William Faux and Russel Earl Helland, Toronto,
Ontario, Canada, assignors to Norman Wade Company
Limited, Scarborough, Ontario, Canada, a corporation
of Canada

Filed May 6, 1965, Ser. No. 85,135

Term of patent 14 years

(Cl. D33—14)

FIG. 1

FIG. 2

FIGURE 1 is a rear perspective view of a drafting table showing our design;

FIGURE 2 is a perspective view, taken from the front showing with the table turned 180° in a horizontal plane from the position of FIGURE 1;

FIGURE 3 is a perspective view of the table turned about 90° clockwise, in a horizontal plane;

FIGURE 4 is a view of the underside of the drafting table.

We claim:

The ornamental design for a drafting table, as shown.
